(57) **CLAIM**

The ornamental design for a video camera, as shown and described.

DESCRIPTION

FIG. 1 is a perspective view of front, top and right side of a video camera showing my new design;
FIG. 2 is a perspective view of rear, top and left side thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.

The broken lines in the drawings are shown to illustrate the portions of a video camera in which the design is embodied and form no part of the claimed design.
